(57) **CLAIM**

The ornamental design for a packaging container, as shown and described.

DESCRIPTION

FIG. 1 is a perspective view of a packaging container showing our new design;

FIG. 2 is a left side view thereof;

FIG. 3 is a right side view thereof;

FIG. 4 is a front view thereof in a closed position;

FIG. 5 is a back view thereof;

FIG. 6 is a bottom view thereof in a closed position; and

FIG. 7 is a top view thereof in a closed position;

FIG. 8 is a top view thereof in an open position;

FIG. 9 is a perspective view thereof in a partially closed position;

FIG. 10 is a front view thereof in an open position; and,

FIG. 11 is a perspective view thereof in an open position.

The broken lines showing of the hands in FIG. 11 are depicted for the purpose of environment and form no part of the claimed design.
